UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

GAS RANGE.

Application filed July 5, 1921. Serial No. 482,388.

To all whom it may concern:

Be it known that I, GEORGE E. PICKUP, a citizen of the United States, residing at Newark, in the county of Licking and State of Ohio, have invented certain new and useful Improvements in Gas Ranges, of which the following is a specification.

The invention relates to gas ranges and has for its aim the provision of a range, in which the parts are compactly arranged and which presents a neat and ornamental appearance.

One object of the invention is to provide an improved arrangement for the gas manifold such that it is wholly concealed from view.

A further object of the invention is to provide in combination with the manifold as it is thus arranged, valve means having readily accessible operating devices for controlling the flow of gas to the burners.

Still another object of the invention is to provide a compact arrangement of the parts such that the distance from the front of the range to the rear is shortened substantially.

Another object is to provide means for protecting the hand of the operator from injury in case of back firing.

The objects of the invention thus generally stated, together with other and ancillary advantages, are attained by the construction and arrangement illustrated in the accompanying drawings wherein I have illustrated one embodiment of the invention. I desire to have it understood, however that although one embodiment only is illustrated, the invention is not limited to the particular form, construction, or arrangement of parts disclosed, since various changes may be made without departing from the spirit and scope of the invention as it is expressed in the appended claims.

Referring now to the drawings, Figure 1 is a fragmentary perspective view of a range embodying my invention. Fig. 2 is a fragmentary top plan view of the forward frame member and illustrating the location of the manifold and flame guard therebelow. Fig. 3 is a front elevational view showing the operating handles for the gas cocks on the forward side of the flame guard. Fig. 4 is a vertical sectional view taken in the plane of line 4—4 of Fig. 3. Fig. 5 is a rear side elevation showing the manifold and the valve means providing a connection between

the manifold and the burners. Fig. 6 is a fragmentary bottom plan section through one of the cocks and the forward end of one of the burners. Fig. 7 is a similar view but showing only a portion of the cock in section, the latter being in this instance provided with a connection for the pilot light.

Referring first to Fig. 1, 8 designates the top frame of the range, having a forward frame member 8^a, and 9 indicates a flame guard mounted upon the under side of the frame member 8^a.

10 is the gas manifold having one end closed and at its opposite end an elbow 10^a with which is connected a suitable gas supply pipe (not shown). Said manifold is located directly below the forward frame member 8^a, and at the under side of the manifold, interposed between it and the burners are the valve means for controlling the flow of gas to the burners. The forward ends only of the latter are shown at 11 in Figs. 4, 6 and 7, being provided with the usual mixing chambers 11^a.

The manifold 10 is preferably made of cast iron, and herein is shown substantially rectangular in form. As a means for supporting the manifold, I provide at its opposite ends bifurcated lugs 12 through which are entered bolts 13 whereby to connect the manifold rigidly to the under side of the forward frame member. The latter, it will be observed, has a downwardly extending flange 14 at its forward edge, and at its rear edge is shaped to provide an angular recess 15 adapted to receive the top or grid plates of the stove. The rear ends of the lugs 12, as shown, extend beneath such rear edge of the frame member, and preferably means such as a washer 16 or studs 16^a is interposed between the under side of the frame member and the lugs on the manifold.

The flame guard 9 is arranged herein to be supported by the manifold 10. Thus the manifold is provided at each end with a bifurcated downwardly extending lug 17 and extending rearwardly from the flame guard, at its opposite ends, are two lugs 18 adapted to engage with the upper side of the manifold. Bolts 19 are then passed through the lugs 17 and the flame guard and serve to secure the latter rigidly to the manifold. As shown in Fig. 4, the upper edge of said flame guard extends adjacent the forward side of the manifold between

the latter and the downturned flange 14 of the forward frame member; and at its lower edge the flame guard may be bent rearwardly as at 20.

- 5 Any desired number of burners may, of course, be employed. Herein I have shown a stove provided with four regular burners and one simmering burner. The cocks for controlling the flow of gas from the manifold to the regular burners are of the type shown in Figs. 4 and 6 and comprise a tubular valve casing 21 having the usual conical valve member 22 therein and communicating by way of a transverse port 23 with a longitudinal passageway 24, which is provided by a parallel tubular stem 24^a and discharges into the forward end of the burner. Upon its upper side the valve casing 21 has an upstanding tubular stem 25 providing a connection between the manifold and the interior of the casing, and the valve member is ported as at 22^a in the usual way so as to be capable of controlling the flow of gas from the manifold to the port 23. The flow of gas from the latter to the passageway 24 may be controlled by means of a needle valve 26. The valve member 22 has the usual operating stem 27 which is equipped with a handle 28.
- 30 It will be observed that the parts of the cock are so arranged as to render possible a location thereof between the manifold and the burner while at the same time permitting the operating stem to extend forwardly through the flame guard 9. The latter for this purpose is provided with suitable apertures 29 which preferably also receive the outer ends of the casing 21 and stem 24^a.
- 40 The needle valve 26 is in the form of a screw having at its inner end a seat 24^b in the passage 24 and at its forward end a head 26^a by means of which it may be readily adjusted to vary the height of the flame at the burner. Preferably the head 26^a of the needle valve also extends through the apertures 29 in the flame guard thus rendering it accessible for adjustment purposes.
- 50 The cock shown in Fig. 7 is adapted to control the flow of gas from the manifold to the simmering burner and also to the pilot light. This cock is substantially similar to the one shown in Fig. 6 except that it provides in addition a connection for the lighting device. Thus, it embodies a tubular stem portion 30 having a transverse port 31 connected with the inlet 25 and a longitudinal passage 33 which communicates with the port 31 and is adapted to be controlled by a needle valve 34 having an adjusting screw 35. The flame guard, it will be understood, is in this instance provided with an aperture 29^a through which the adjusting screws 35 as well as the valve stem 27 and the screw 26^a may pass.

It will be seen that I have produced in a gas range a novel and advantageous arrangement for the gas manifold, and a valve means adapted thereto for controlling the flow of the gas. By this arrangement, the entire valve means, with the exception of the operating and adjusting means are wholly enclosed, and as to the latter they are rendered readily accessible. The range thus not only presents a neat appearance but the parts are protected from grease and dirt so that the usual difficulty encountered in keeping these parts clean is eliminated. Moreover, by locating the manifold directly beneath the forward frame member the distance from front to rear of the stove is materially shortened, and this without any sacrifice in efficiency.

The construction is relatively simple and permits of the use of a manifold of cast iron which requires no finishing; and the flame guard which I have provided in addition to enclosing unsightly parts, constitutes an effective means for preventing injury to the operator by reason of back firing.

The valve means herein disclosed is described and claimed in my copending application Serial No. 482,387, filed July 15, 1921.

I claim as my invention:

1. In a gas range, the combination of a top frame comprising a forward frame member, a manifold secured to the under side of said frame member, and valve means for controlling the flow of gas to the burners having a connection with the manifold at the under side thereof, operating means extending forwardly thereof, and discharge means located laterally to one side of the operating means.
2. In a gas range, the combination of a stove top comprising a forward frame member, a manifold mounted below said frame member, an upright member mounted forwardly of said manifold, and valve means comprising a casing communicating with said manifold and having an operating stem extending through said upright member.
3. In a gas range, the combination of a manifold, valve means for controlling the flow of gas therefrom to the burners, and means for enclosing said manifold comprising an upright member mounted forwardly of the manifold and projecting in a perpendicular relation with reference thereto, said valve means having an operating member projecting through said enclosing member.
4. In a gas range, the combination of a top frame, a burner located beneath the top frame and having a forwardly extending portion with a mixing chamber at its forward end, a manifold located beneath the forward portion of the top frame, valve means disposed between the manifold and the mixing chamber, and an apertured plate

- also located below the top frame in front of the manifold and serving to enclose the major portion of the valve means, the latter being rendered accessible for operation or 5 adjustment by the apertures in the plate.
5. In a gas range, the combination of a stove top, a manifold secured to the under side of said top, valve means carried by said manifold, and a member also carried by the 10 manifold coacting with the stove top to enclose the manifold and the valve means, said member having apertures therein, and operating means for the valve means projecting through said apertures.
- 15 6. In a gase range, the combination of a
- stove top having a front frame member, a manifold located beneath said frame member, a gas cock communicating with said manifold and having an operating stem projecting forwardly with respect to the manifold, and a flame guard between the operating means and the manifold.
7. In a gas range, the combination of a top frame, a burner, means for supplying gas to the burner, including a valve, a handle 25 for the valve, and a flame guard between the burner and said handle.

In testimony whereof, I have hereunto set my hand.

GEORGE E. PICKUP.
